UNITED STATES PATENT OFFICE.

THOMAS S. KEMBLE, OF CLEVELAND, OHIO.

ADJUSTING TOOL.

Application filed January 24, 1921. Serial No. 439,542.

The present invention relates to valve adjusting tools for the valves of internal combustion engines whereby adjustment may be made to maintain the proper working relation between the valve stems and the mechanism by which each valve is operated.

An object of the invention is to provide a construction in which the process of adjustment can be simplified beyond the ordinary method.

Reference should be had to the accompanying drawings forming a part of this specification in which Fig. 1 shows partly in elevation and partly in sectional elevation a valve seat of an engine with cooperating valve and valve stem or rod of the present invention applied thereto, together with one form of operating mechanism; Fig. 2 is an elevation showing one of the members of the construction shown in Fig. 1; Fig. 3 shows in side elevation a portion of the upper part of a valve rod with a tool by which adjustment may be effected; Fig. 4 is a top plan view of the showing in Fig. 3; Fig. 5 is an end elevation with portions in section of the showing in Fig. 3.

In internal combustion engines with poppet valves it is necessary to make an adjustment between the valve stems and the mechanism by which they are operated. This adjustment is used, first, to make up for inaccuracy in the manufacture of the parts, and second, to make up for wear and other changes such as lapping valves and valve seats in the cylinders.

The present invention provides a simple tool by which accurate adjustment of the valve may be quickly and easily made.

Referring to the drawings, 1 indicates a portion of an automobile, more particularly an engine head, in which there is provided an opening 2 provided with a seat 3, and cooperating with the seat is a valve head 4 which may be constructed in the usual and well known manner. As will be understood, the opening 2 may be considered to be an intake or an exhaust port for an internal combustion engine, and the valve 4 and valve stem which periodically is moved to permit the passage of carbureted air or exhaust gases as the case may be.

The valve head 4 is formed with a stem or rod 5, which at its upper end is threaded, as indicated at 6, and cooperating with the threaded end of the stem 5 is an adjusting

member 7. This adjusting member has an upper portion 7^a which is formed with a plurality of sides, that is to say, it may be hexagonal, octagonal, or any other similar form. The upper portion 7^a is or may be 60 provided with a shoulder as indicated at 7^b, for the reception of an operating tool, as will later be described.

The head member 7 has a reentrant bore or opening 7^c, this opening being threaded, 65 as clearly shown in the drawing. The outer wall of the lower portion is slanting toward the longitudinal axis of the member 7, or in other words is of frusto-conical shape, as indicated at 7^d.

This portion of the member 7 which is conically shaped, as before indicated, is provided with a plurality of slots, which is indicated at 7^e. These slots divide the lower portion of member 7 into a plurality of 75 jaws for gripping the threaded end of the valve stem to prevent displacement of the adjusting member during operation of the valve.

Surrounding the lower or conically shaped portion of the member 7 is a washer 8. This washer has a central opening which has a conically shaped inner wall, such as indicated at 8^a, the degree of slant of the wall 8^a being complementary of the degree of 85 slant of the conical portion of the member 7. The member 8 has outwardly extending portions such as indicated at 8^b and with these outwardly extending portions the usual springs 9 cooperate, the lower ends of 90 the springs 9 being suitably supported upon the head of the engine which is a usual and very well known construction.

The springs 9 tend to maintain the valve 4 in closed position and the functioning of the 95 valve, that is to open, is controlled by a mechanism cooperating with the valve stem which in the present instance is a rocker arm, such as shown at 10, which rocker arm is centrally pivoted, as illustrated at 11^a, 100 and at one end the arm 10 is provided with a face 11, which cooperates with the member 7. The opposite end of the rocker arm 10 is pivotally connected with a rod 12, which in turn is suitably operated by a cam shaft, 105 or equivalent device, in a manner which is or may be that commonly employed.

It will be obvious that by movement of the member 7, the effective length of the valve stem 5 may be adjusted with respect 110

to the face 11 so as to maintain the proper relationship between these two cooperating parts.

In effecting an adjustment of the member 5 with respect to the valve stem 5, it is necessary to depress the washer 8 relative to the member 7 and at the same time to prevent the valve stem 5 from turning, whereupon the member 7 may be turned in the proper direction to effect the desired degree of adjustment.

In order to provide a means by which this adjustment may be quickly and effectively made, there is shown in Figs. 4 and 5, a tool 15 which is suitable for the purpose. This tool comprises two members 15 and 16 which are pivoted to each other by a pin which is indicated at 17. These members 15 and 16 have handles or hand engaging portions as 20 indicated at 15^a and 16^a and the shape and cooperation of the members 15 and 16 is such that the handles 15^a and 16^a are separated when the forward portions, or those portions of the members 15 and 16 which 25 lie beyond the pivot 17, are in cooperating position.

The member 15 at its forward end has a reentrant portion such as indicated at 15^a, the opposite side parts of which engage opposite flat sides of the enlarged portion 7^a of the adjusting nut and along the lower edges of the opposite side parts of the reentrant portion there are inwardly extending flanges 15^b. These flanges are adapted to 30 enter between the shoulder 7^b at the inner side of the portion 7^a of the adjusting member and the washer, the manner of their engagement being clearly illustrated in Fig. 5. The forward extremities of the member 16 35 will bear upon the outer face of the washer 8 which engagement is clearly shown in Fig. 5 and when in this position the handles 15^a and 16^a may be pinched together by the hand of the operator which will cause the 40 washer 8 to be depressed with respect to the member 7, and against the action of the spring 9. This operation will of course compress the springs and increase the pressure with which the valve 4 is held against 45 its seat and, due to the fact that there is considerable friction between the engaging portions of the valve 4 and its seat 3, opposing rotation, the members 15 and 16 when 50 positioned and operated to hold the adjusting member away from the washer, may be turned either clockwise or counterclockwise, and thereby cause the member 7 to turn relative to the valve stem 5, the member 16 55 turning upon the outer face of the washer as the adjusting member or nut is turned. When the pressure pinching the handles together is released, the washer is permitted to reengage the member 7, thus locking it in its new position relative to the valve stem.

60 Having described my invention, I claim:

1. A tool for freeing a nut from a locking washer engaging the same and for turning the nut while held free of its locking washer comprising means for nonrotatably engaging the nut to turn the same, and means connected to said first mentioned means and coacting therewith to force the washer and nut apart and to hold the washer free of the nut and said first mentioned means in engagement with the nut, whereby said nut may be turned while held free of the locking member.

70 2. Means for freeing a nut from a locking washer engaging the inner side of the nut and for turning the nut while held free of its locking washer comprising a tool having a nut engaging part engageable with the inner side of the nut and adapted to non-rotatably engage the nut, and a second part connected to the first part and engageable with the outer face of the washer, said parts being movable to force the washer and nut apart and to turn the nut while it is held free of the washer.

75 3. A tool for freeing a nut from a locking washer engaging the same and for turning the nut while held free of its locking washer comprising a rigid member adapted to non-rotatably engage the nut to turn the same, said tool having a part cooperating with said rigid member to press the same against the nut and to force the nut and locking washer apart and to hold the nut and locking washer apart while the nut is being turned.

80 4. An adjusting tool for a poppet valve for internal combustion engines which has upon its stem at the outer end thereof a nut and a spring pressed washer engaging the inner side of the nut comprising a pair of members pivoted to each other, one of said pivoted members being engageable with the washer and the other of said pivoted members being engageable with the nut whereby when the tool is applied to the nut and washer and the pivoted members are moved about their pivotal connection the washer is separated from said nut, the first mentioned pivoted member being adapted to rotate on the washer and the second pivoted member being adapted to non-rotatably engage with the nut whereby when the tool is turned said nut is rotated on the stem.

85 5. A tool for adjusting a poppet valve having upon its stem at the outer end thereof a nut and a spring pressed washer engaging the inner side of the nut comprising pivoted jaws, one jaw having parts adapted to embrace the nut at the outer end of the valve stem and engage the inner side thereof and the other jaw adapted to bear against the outer side of the spring pressed washer and slide thereon, whereby when the jaws are separated the washer is disengaged from the nut and the valve is held to its seat and

against rotation whereby the tool may be turned to adjust the nut on the valve stem.

6. A tool for adjusting a poppet valve having upon its stem at the outer end thereof a nut and a spring pressed washer engaging the inner side of the nut comprising a pair of pivoted jaws, one of said jaws having a forked end adapted to fit over the nut

and flanges extending inwardly from the forks thereof to engage the inner side of the ¹⁰ nut and the other jaw being adapted to bear against the outer face of the washer, and operating handles connected to the jaws.

In testimony whereof, I hereunto affix my signature.

THOMAS S. KEMBLE.
